CLAIM

The ornamental design for a pill container system, as shown and described.

DESCRIPTION

FIG. 1 is a perspective view of a pill container system showing my new design;

FIG. 2 is a right side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view thereof, shown in use.
